[57] CLAIM

The ornamental design for a top for a sink, as shown and
described.

DESCRIPTION

FIG. 1 is a perspective view taken from the top, front
and right side of a top for a sink showing our new de-
sign;

FIG. 2 is a top plan view thereof;

FIG. 3 is a cross-sectional view taken on line 3—3 of
FIG. 2; and,

FIG. 4 is a cross-sectional view taken on line 4—4 of
FIG. 2.

The fragmentary broken line representation of a sink
basin in FIGS. 3 and 4, and of a countertop in FIG. 1,
are for the purpose of illustration only and form no part
of the claimed design.
